UNITED STATES PATENT OFFICE.

DAVID M. PARRY AND THOMAS H. PARRY, OF INDIANAPOLIS, INDIANA.

SPRING-SUPPORT FOR VEHICLES.

SPECIFICATION forming part of Letters Patent No. 398,180, dated February 19, 1889.

Application filed November 17, 1888. Serial No. 291,164. (No model.)

To all whom it may concern:

Be it known that we, DAVID M. PARRY and THOMAS H. PARRY, citizens of the United States, residing at Indianapolis, in the county 5 of Marion and State of Indiana, have invented certain new and useful Improvements in Spring-Supports for Vehicles; and we do hereby declare the following to be a full, clear, and exact description of the invention, such as 10 will enable others skilled in the art to which it appertains to make and use the same.

This invention in two-wheeled vehicles relates especially to improvements in spring-supports, the object of the invention being 15 to so construct a spring-support that it will be cheap, durable, efficient, and practically anti-frictional, and to so connect it to the shaft of the vehicle that it may automatically adjust itself to the various positions of the vehicle- 20 spring which is connected at its ends to said support and allow said spring to move vertically and horizontally, and to provide a connection between said support and shaft of such construction and arrangement that the 25 support may be quickly and easily connected and disconnected from the shaft without the necessity of removing bolts, &c.

We are aware that a spring has been pivotally connected to the shafts of a vehicle by 30 means of straps or double shackles, which shackles are pivoted at one end to a plate secured to the shafts and at the other end to the spring by bolts, said shackles being each formed from a strip of bar-iron with a hole 35 punched in each end, through which the bolts are extended, as described in Patent No. 266,895, dated October 31, 1882; but this construction we do not desire to claim.

With the objects in view above stated our 40 invention consists, primarily, in a spring-support for vehicles, comprising a hanger having a bolt or lug at its lower end to be engaged by the end of the spring and having a vertically-elongated opening at its upper end, 45 a plate secured to the shaft having a hook-shaped end with a horizontally elongated or enlarged head to enter the elongated opening in the hanger when the hanger is turned to a horizontal position, and prevent the dis- 50 placement of the hanger when in a depending position, said hook-shaped end of the fast-

ening-plate forming an axis upon which the hanger oscillates during movement of the spring, substantially as and for the purpose hereinafter described, and set forth in the 55 claims.

It also consists in certain details of construction, and in the combination and arrangement of the several parts of the spring-support, substantially as hereinafter described 60 and claimed.

Figure 1 represents in side elevation a spring-support for vehicles constructed in accordance with our invention, a portion of one shaft only of the vehicle being shown; 65 Fig. 2, a front view of the same, and Fig. 3 a modified construction of support.

In the drawings, A represents the hanger, and B the attaching-plate, to which the hanger is pivoted and by which it is movably secured 70 to the shaft D of the vehicle. The hanger A will preferably be constructed of a single piece of bar or round wrought-iron bent at its center to form a loop or elongated eye, a', the ends being crossed or overlapped at a 75 point below the bend, as at a², Fig. 1, and the two ends below the overlap being spread or remote from each other to form a bifurcated or forked lower end, a³, the extreme ends being flattened and punched to form bolt-holes, 80 through which a spring-supporting bolt, a⁴, is extended, said bolt being secured by a nut, a⁵, at the outer face of one of the ends of the hanger A.

If desired, a friction-roller may be mounted 85 upon the bolt.

The bolt a⁴ is engaged by the curved end c' of the vehicle-spring C.

It will be understood that there is one spring support or hanger secured to each 90 shaft, and that one end of the spring engages one and the opposite end the other of said supports or hangers, the spring being secured at its central portion to the body or seat of the vehicle. Therefore, to obviate confusion, 95 the specification describes but one support and its parts, both supports being substantially alike.

If desired, the hanger may be made, as illustrated in Fig. 3, from a single rod bent to 100 form an oblong opening at its lower end, the cross or end bar, a⁴, of which supports the end

of the spring, and welded, flattened, and punched at its other end to form an elongated eye to engage the hook upon the fastening-plate B. This fastening-plate will preferably 5 be constructed of malleable iron, with an outwardly and upwardly projecting portion or hook-shaped projection, b' , formed integral therewith, said hook having at its upper end a horizontal elongated head, b^2 , the length 10 and breadth of which are approximately the same as the slot in the upper end of the hanger A, said head b^2 being adapted to enter the slot or eye a' when the hanger is turned upward to a horizontal position, the lower or 15 horizontal portion of the hook forming an axis upon which the hanger swings during movement of the spring C.

By this construction of hanger and attaching-plate it will be seen that in the normal or 20 depending position of the hanger the elongated head b^2 overlaps the edges of the eye a' in the hanger, and that a vertical movement would not displace the said hanger, and that by turning the hanger upward edgewise upon 25 its axis the eye a' and head b^2 would register with each other and the hanger could be quickly removed. This plate B will preferably have a flanged barb or burr, b^3 , upon its rear face to be driven into the shaft D, a bolt, 30 b^4 , being extended through the shaft and plate to secure the same.

The spring will be of the usual semi-elliptical form, it having an eye, c' , at its either end, through which the spring-supporting bolt a^4 is extended, said spring end being interposed between the ends of the hanger. 35

If the hanger illustrated in Fig. 3 is used, the spring will have its ends bent partially around and hooked over the spring-supporting bar. 40

We claim—

1. In combination, the hanger A, constructed from a single piece of wrought metal, having an elongated vertical eye at its upper end and a spring-supporting lug at its lower end, and 45 the plate B, having the headed hook to engage the hanger, and the burr or flange to enter the shaft, said plate being secured by a bolt or otherwise, substantially as set forth.

2. In a spring-support for vehicles, a hanger 50 constructed from a single piece of wrought metal, having an elongated eye at its upper end and a removable spring-support at its lower end, as described.

In testimony whereof we affix our signatures 55 in presence of two witnesses.

DAVID M. PARRY.
THOMAS H. PARRY.
